ATTACHING MEANS

Carl A. Flood, Framingham, Mass., assignor to
Dennison Manufacturing Company, Framing-
ham, Mass., a corporation of Massachusetts

Application May 7, 1935, Serial No. 20,137

15 Claims. (Cl. 223—102)

This invention relates to a device for passing a strand through material and to a corresponding method such as may be practiced by employment of the device.

The present invention may be particularly employed in attaching a tag to an article such as an article of wearing apparel or a sheet of fabric, and is particularly adapted to use with fastening devices such as disclosed in my copending application Serial No. 723,170, filed April 30, 1934, in which I have disclosed an attaching device which comprises a generally tubular retainer in which the oppositely extending end portions of a string loop are received, the adjoining portions of the string normally tending to extend at right angles from the intermediate part of the retainer, and providing a string loop which may extend through an opening in a suitable tag, such as a price tag. My copending application Serial No. 723,171, filed April 30, 1934 disclosed a needle for securing such fastening devices to a sheet article or the like. The present invention provides an improved device for this purpose. This invention affords an arrangement which facilitates the handling of the relatively small attaching bar and its convenient movement into proper engagement with the attaching device. Furthermore, the present invention permits the convenient movement of the retaining bar along the attaching apparatus after the same has been properly positioned in relation to the article with which the retaining bar is to be associated. For this purpose I may provide a hollow needle which is connected to a frame upon which a slidable plunger is mounted to move into a bore in the needle, the guiding or feeding means being arranged so that the retaining bar may readily be positioned in alignment with the outer end of the bore of the needle, whereupon the plunger may be advanced to push the bar along the bore of the needle. A suitable opening is provided near or at the point of the needle so that the bar may be ejected when it reaches this portion of the bore. In order to permit an attaching device, including a bar and string, to be inserted by apparatus of the class described, a longitudinal slot is provided in the needle to communicate with the bore. Thus, while the bar is being moved through the bore of the needle, the string extending from the bar may extend through the slot and may move along the same until it engages the sheet material through which the needle has been inserted. Thereupon the bar may continue its movement to the region of ejection adjoining the point of the needle, while the string extends along the needle to the

point where it intersects the plane of the sheet material. When the bar is ejected, for example upon the inner side of the fabric, it may be effective in holding the end of the string loop in place, while the string extends through the opening in the sheet material which was formed by the needle. Thus, in a typical example of the use of this invention, the retaining bar may be moved through the fabric sheet material so that it may engage one face thereof, the strings extending from the bar extending through an opening in the material to provide a loop supporting a tag, such as a price tag, upon the opposite side of the fabric.

In the preferred embodiment of the invention the needle may be arranged so that it may be retracted into a hollow frame or handle when the device is not in use. The plunger may be operated by an actuating element or a thumb piece which is normally slidable along a slot provided by the handle.

In the accompanying drawing:

Fig. 1 is a plan view of a device constructed in accordance with this invention;

Fig. 2 is a side elevation of the same, certain parts being broken away and shown in section, and certain parts being shown in their retracted positions by dotted lines;

Fig. 3 is a bottom view of the device shown in Fig. 1;

Figs. 4 and 5 are sections indicated by lines 4—4 and 5—5, respectively, of Fig. 2;

Fig. 6 is a section on line 6—6 of Fig. 1;

Fig. 7 is a side elevation of a portion of the device in use, parts being removed and shown in section, and a sheet article being indicated in dot and dash lines;

Fig. 8 is a vertical section of the needle portion of the device;

Fig. 9 is a fragmentary view showing a fastening device which has been applied to a sheet article by apparatus of the type disclosed herein;

Fig. 10 is an isometric view of a portion of such a fastening device; and

Fig. 11 is a sectional detail showing an optional form of needle.

The accompanying drawing illustrates a typical preferred embodiment of my invention and shows a hollow needle 1 the end of which is beveled as designated by numeral 2. The needle is provided with a cylindrical bore 3 which has an open end at the beveled or pointed end of the needle and an opposite generally cylindrical end 1^a of enlarged diameter, in which a plunger 4 which is in the form of a straight wire may move. The needle is

also provided with a longitudinal slot 5. The blunt end of the needle is clamped between a guide plate 6, which is provided with a flared upper flange 7, and guide blocks 8 and 9 which are connected to the plate 6 by fastening means 10 such as rivets or screws. The plate 6 and the blocks 8 and 9 define a recess 11 to receive the tubular bar of the attaching device. The adjoining edges of the blocks 8 and 9 are spaced to define a vertical slot 12 shown particularly in Fig. 2. The needle provides an opening 14 which connects the slot 12 and the slot 5 as shown in Fig. 3. Thus when a bar is inserted into the recess the string connected to the bar may pass through the slot 12 and through the slot 14, the latter communicating with the slot 5 of the needle. The plunger 4 is reciprocable in the bore 3, being retractible to a position wherein its end is spaced from opening 14, as shown in Fig. 7.

Members 6 and 7 may conveniently be integral with a frame or guide member 21 which has a generally rectangular body portion with an inner wall 22 which in effect forms a stop for the plunger, as will presently be described, with parallel side walls 23 and with adjoining coplanar outer wall portions 24 which may be connected to or integral with the plate 6 and the block 9, as shown. Preferably the walls 23 may also be flanged over to provide longitudinal flanges 26, as shown in Figs. 1 and 5. The flanges 26 rest upon the inturned flanges 27 of an outer handle member 28 which has a lower portion which is generally semi-cylindrical in cross section, as shown in Fig. 5, and has parallel side walls. The end of the handle portion remote from the needle may be provided with an end wall 29.

An opening is provided in the opposite end of the handle member 28 to receive a stud 30 mounted on the end of a leaf spring 31, the opposite end of this spring being extended upwardly to hook about the end wall 22 of the frame 21, as designated by numeral 33. Thus when the parts are in the normal operative position shown, for example, in Fig. 2, the spring 31 is effective in holding the needle in its advanced position relative to the handle 28. However, when the device is not in use, the projecting end 31^a of the spring may be pressed upwardly to remove the stud 30 from the opening in the handle so that the entire assembly may be slid to the right, as viewed in Fig. 2, to occupy the retracted position shown in Fig. 2. When it is desired to return the needle assembly to the normal operative position it may be moved toward this position by taking hold of the flange 7 and sliding the assembly to the left until the stud 30 snaps into engagement with the opening in the handle.

The plunger 4 is provided with an actuating element 40 in the form of a thumb piece having an upper portion resting upon the flanges 26 of the frame 21 and having depending portions in the form of two ears 43. Openings are provided in these ears through which the plunger 4 extends, the end of the plunger being bent about the portion of the ear which is remote from the needle; thus this portion of the plunger provides a generally hooked wire section designated by numeral 44, Fig. 2.

Apparatus of the character which has been described may be used with particular facility in proper position attaching devices such as disclosed in my copending application Serial No. 723,170. Such a device is shown in Fig. 10 and includes a generally tubular retaining bar B in the end portions of which the opposite ends of a strand or

string S are secured. Strand portions extend from the intermediate part of the tubular bar and commonly provide a loop in engagement with a price tag T or the like, Fig. 9.

When apparatus of the character described is to be employed in inserting such a retaining bar through a fabric sheet or the like, the handle 28 of the device may be grasped by the operator and the point of the needle 1 inserted through the sheet article A in the position illustrated in Fig. 10. The member 40 is retracted so the hook portion 44 of the plunger engages wall 22 as a stop. A bar B may then be engaged with the feeding and guiding portion of the device, for example the bar may first be conveniently pressed against flange 7 and the string S be initially disposed in the upper part of the slot 12; thereupon the bar may be moved downwardly into the recess 11 adjoining the end of the needle, the string S being pulled to aid this movement until it hangs downwardly in registration with the end of slot 5, Fig. 2. Thereupon the actuator 40 may be slid toward the needle to cause the end of plunger 4 to engage the bar B, moving the latter into and along the bore 3 of the needle. As this movement continues, the string S may move along the slot 5 of the needle, and, when the mid-portion of the bar B moves beyond the plane of the sheet article A, the string S engages the edge of the opening in the sheet material. As this movement is continued, the bar is ejected from the beveled end of the needle and the string passes through the slot 5 and out of engagement with the needle. Thereupon the needle may be withdrawn from the sheet article leaving the bar B in the position shown in Fig. 9 wherein the string S extends through the opening that was formed by the needle and the tag T is disposed at the opposite face of the sheet article. Thus the retaining bar is positioned to prevent its movement through the fabric and the string loop is firmly anchored to the sheet article.

Fig. 11 illustrates an optional type of needle which may be employed with apparatus having the general construction which has been described. When such a needle is employed, a plunger 104, similar to the plunger 4, may be provided to reciprocate in the needle 101, which has a solid point with its bore terminating adjoining the point. This bore is provided with a longitudinal slot, similar to the slot 5, but the end portion of the slot is enlarged to provide an opening 105 through which a bar B may be ejected. To aid in this movement of the bar, the end of the bore is provided with a curved cam-like surface 106.

It is evident that this type of needle may be arranged and employed in the general manner described with reference to the embodiment of the invention illustrated in Figs. 1 to 8 inclusive. The type of needle shown in Fig. 11 is advantageous, since the gradually tapered solid point is particularly effective in penetrating fabric or the like without tending to tear the same.

It is evident that apparatus of this character may be employed in a wide variety of environments where it is desired to be able quickly to secure a strand to a sheet article. For example, the present invention may conveniently be employed for securing a tag to a portion of a lining of a garment or article of wearing apparel such as the lining of a hat, it being evident that the retaining bar may be inserted through the lining without necessity for access to the inner surface of the same. Thus a price tag may con-

veniently be secured, for example, to the lining of a hat being held in place in this manner until the hat is to be worn, whereupon the string sections may be cut to permit the removal of the tag. It is evident that the present invention is particularly effective in facilitating the connection of attaching devices including retaining bars to sheet articles without necessity for particularly fine and accurate operations, such as are required when, for example, individual bars have to be manually inserted in small recesses in needles. The bar, although it is small, may readily be engaged with the guide portion of the apparatus, and due to the flared shape of the upper portion of recess 11, may readily be moved downwardly into the position shown in Fig. 2, the string S being movable into registration with the end of the slot 5. When the bar and string are once positioned, as shown in Fig. 2, the plunger then may be almost instantaneously advanced to move the bar through the plane of the sheet article, whereupon the needle may be withdrawn leaving the bar in the desired position.

It should be understood that the present disclosure is for the purpose of illustration only and that this invention includes all modifications and equivalents which fall within the scope of the appended claims.

I claim:

- 30 1. A device of the class described comprising a needle having a longitudinal bore, a plunger, means to reciprocate the plunger along the needle, said needle having on one side a longitudinal slot to receive a flexible element depending from a fastening bar disposed within the bore, whereby the plunger may advance the bar through the bore, and said needle having on another side an opening for inserting a fastening bar in said bore.
- 40 2. A device of the class described comprising a needle having a point and a longitudinal bore extending from the opposite end of the needle to a region near the point, the wall of the bore providing a slot and a communicating opening in the region of the point, and a plunger movable in the bore, whereby a fastening device including a bar and a string extending therefrom may be disposed with the bar in the bore and the string in the slot, and the plunger may be advanced to push the bar while the string moves along the slot, the bar being ejected when it reaches said opening, said wall having an opening circumferentially offset from said slot through which bars may be fed to said bore.
- 50 3. A device of the class described comprising a needle having a point and a longitudinal bore extending from the opposite end of the needle to a region near the point, the wall of the bore providing a slot and a communicating opening in the region of the point, and a plunger movable in the bore, and a feeding guide secured to the end of the needle remote from its point, said guide having a recess communicating with the end of the bore and a slot communicating with the slot of the needle, whereby a fastening device consisting of a bar and string may be disposed with the bar in the recess and the string in the last-named slot and the plunger may be advanced to push the bar through the bore and opening while the string moves along said first-named slot.
- 60 4. A device of the class described comprising a tubular needle portion having a longitudinal bore and a beveled end to provide a point, said beveled end having an opening therein, the bore extend-

ing to said opening, a plunger, means to reciprocate the plunger into and along the bore of the needle, said needle having a longitudinal slot to receive a flexible element depending from a fastening bar disposed within the bore and being 5 propelled by the plunger, whereby the plunger may advance the bar through the bore.

5. A device of the class described comprising a tubular needle having a longitudinal bore and a beveled end to provide a point, the bore extending to an opening at the beveled end of the needle, a plunger, means to reciprocate the plunger into and along the bore of the needle, said needle having a longitudinal slot to receive a flexible element depending from a fastening bar disposed 10 within the bore and being propelled by the plunger whereby the plunger may advance the bar through the bore, and a guide to facilitate movement of the bar into the needle, the device providing a recess to receive a bar in alignment with the bore 15 of the needle, said guide having a slot extending along its side and communicating with the slot of the needle, whereby the bar may be located in the recess and the string attached to the bar may be moved into the slot of the needle. 25

6. A device of the class described comprising a tubular needle having a longitudinal bore and a point, the bore extending to an opening near the point of the needle, a plunger, means to reciprocate the plunger into and along the bore of the 30 needle, said needle having a longitudinal slot to receive a flexible element depending from a fastening bar disposed within the bore and being propelled by the plunger whereby the plunger may advance the bar through the bore, a guide to 35 facilitate movement of the bar into the needle, said device providing a recess to receive a bar in alignment with the bore of the needle, the guide having a slot extending along its side and communicating with the slot of the needle, and a 40 flared flange upon the opposite side of the guide to facilitate the movement of a bar into the recess.

7. A device of the class described comprising a tubular needle having a longitudinal bore and a 45 point, the bore extending to an opening near the point of the needle, a plunger, means to reciprocate the plunger into and along the bore of the needle, said needle having a longitudinal slot to receive a flexible element depending from a fastening bar disposed within the bore and being 50 propelled by the plunger whereby the plunger may advance the bar through the bore, a guide to facilitate movement of the bar into the needle, said guide providing a recess to receive a bar and 55 having a slot extending along its side and communicating with the slot of the needle, whereby the bar may be located in the recess and the string attached to the bar may be moved into the slot of the needle, a handle means connected to the guide, and an actuator secured to the plunger 60 and movable along a slot in said handle means.

8. A device of the class described comprising a tubular needle having a longitudinal bore and a point, the bore extending to an opening near the 65 point of the needle, a plunger, means to reciprocate the plunger into and along the bore of the needle, said needle having a longitudinal slot to receive a flexible element depending from a fastening bar disposed within the bore and being 70 propelled by the plunger whereby the plunger may advance the bar through the bore, a guide to facilitate movement of the bar into the needle, said guide providing a recess to receive a bar and having a slot extending along its side and com- 75

municating with the slot of the needle, whereby the bar may be located in the recess and the string attached to the bar may be moved into the slot of the needle, a frame connected to the guide, 5 an actuator secured to the plunger and slidable along the frame, and a hollow handle in which the frame is supported.

9. A device of the class described comprising a tubular needle having a longitudinal bore and a point, the bore extending to an opening near the point of the needle, a plunger, means to reciprocate the plunger into and along the bore of the needle, said needle having a longitudinal slot to receive a flexible element depending from a fastening bar disposed within the bore and being propelled by the plunger whereby the plunger may advance the bar through the bore, a guide to facilitate movement of the bar into the needle, said guide providing a recess to receive a bar and

10 having a slot extending along its side and communicating with the slot of the needle, whereby the bar may be located in the recess and the string attached to the bar may be moved into the slot of the needle, a frame connected to the guide, an 15 actuator secured to the plunger and slidable along the frame, and a hollow handle in which the frame is supported, said frame being slidable into said handle to permit the needle to be moved to a retracted position within the handle.

10. A device of the class described comprising a tubular needle having a longitudinal bore and a beveled end to provide a point, the bore extending to an opening at the beveled end of the needle, a plunger, means to reciprocate the plunger into and along the bore of the needle, said needle having a longitudinal slot to receive a flexible element depending from a fastening bar disposed within the bore and being propelled by the plunger whereby the plunger may advance 20 the bar through the bore, a guide to facilitate movement of the bar into the needle, said guide providing a recess to receive a bar and having a slot extending along its side and communicating with the slot of the needle, a frame connected 25 to the guide, an actuator secured to the plunger and slidab'e along the frame, a hollow handle in which the frame is supported, said frame being slidable into said handle to permit the needle to be moved to a restricted position within the

30 handle, and spring means normally holding the frame and needle in operative position, said means being releasable to permit the frame and needle to be moved to retracted position.

11. A device of the class described comprising 35 a needle having a solid point and a longitudinal bore extending from the opposite end of the needle to a region near the point, the wall of the bore providing a slot and an opening communicating with the slot in the region of the needle point, and a plunger movable into the bore, said wall having an opening circumferentially offset from said slot, whereby a fastening device includ-

ing a bar and a string extending therefrom may be disposed with the bar in the bore and the string in the slot, and the plunger may then be advanced to push the bar while the string moves along the slot, the bar being ejected when it reaches said opening. 5

12. A device of the class described comprising a needle having a solid point and a longitudinal bore extending from the opposite end of the needle to a region near the point, the wall of the bore providing a slot and an opening communicating with the slot in the region of the needle point, the end of the bore adjoining said opening having a curved cam-like surface, and a plunger movable into the bore, said wall having 10 an opening circumferentially offset from said slot, whereby a fastening device, including a bar and a string extending therefrom, may be disposed with the bar in the bore and the string in the slot, and the plunger may then be advanced 15 to push the bar while the string moves along the slot, the bar being ejected when it reaches said opening and engages said cam-like surface.

13. A device for inserting a headed strand through material, comprising a needle and having 20 a hollow bore with an exit near the point of the needle and a longitudinal slot through the wall of said bore, said wall having another opening circumferentially offset from said slot and a circumferential slot interconnecting said opening 25 with said longitudinal slot, whereby the headed strand may be inserted through said opening into said bore and the strand passed along said circumferential slot to said longitudinal slot, and a plunger in said bore for then propelling the 30 headed strand along said bore and thence through 35 said exit.

14. A device for inserting a headed strand through material, comprising a needle and having 40 a hollow bore with an exit at one end near the point of the needle and an inlet at the other end and a slot through the wall of said bore from said inlet to said exit, said inlet being wider than the slot so that the head of the strand 45 may be inserted through the inlet into and thence along said bore with the strand passing along said slot, and a plunger in said bore for propelling said head along said bore and thence through said exit.

15. A device of the class described comprising 50 a needle for piercing fabric and the like and an enlarged head in the rear of the needle, said head and needle having aligned bores with an inlet and an outlet respectively communicating with said bores for inserting and ejecting a headed 55 strand, and a plunger reciprocatable in said bore, whereby the needle may be inserted through fabric or the like until the fabric abuts said head and the headed strand may then be passed through the fabric by advancing said plunger. 60

CARL A. FLOOD.
